UNITED STATES PATENT OFFICE.

ALBERT H. ARMSTRONG, OF SCHENECTADY, NEW YORK, ASSIGNOR TO GENERAL ELECTRIC COMPANY, A CORPORATION OF NEW YORK.

SLIDING CURRENT-COLLECTOR.

No. 888,382.

Specification of Letters Patent.

Patented May 19, 1908.

Application filed August 6, 1906. Serial No. 329,296.

To all whom it may concern:

Be it known that I, ALBERT H. ARMSTRONG, a citizen of the United States, residing at Schenectady, county of Schenectady, State of New York, have invented certain new and useful Improvements in Sliding Current-Collectors, of which the following is a specification.

The present invention relates to electric railways, and more especially to the contact devices carried by the vehicles for collecting current from a stationary conductor suspended parallel to the road way.

When currents of large volume are to be transmitted to an electric locomotive or other vehicle of great power the ordinary grooved wheel trolley is objectionable on account of the excessive sparking which occurs between it and the stationary conductor due to the inadequate area of contact between such parts. Accordingly, it is the present practice on vehicles requiring large volumes of current to provide a sliding contact having ample area of contact with the stationary conductor. These sliding contacts have been made with considerable length with the intent to provide a large surface to sustain the wear due to the frictional action of the stationary conductor thereon, but it is the rule rather than the exception that one or more depressions are soon formed across the contact which tend to prevent the conductor from engaging the contact at any other line and as a consequence one or more deep ruts or grooves are soon cut in the surface of the contact, so that renewals are frequently required although the greater portion of the contact may be good as new.

The object of my invention is to provide a contact device so constructed that by a simple adjustment any cutting or rutting in its working surface may be cured.

In the accompanying drawing which forms a part of this specification, I have shown one embodiment of my invention.

Figure 1 is a perspective view of my contact device mounted upon the roof of an ordinary passenger car. Fig. 2 is a side elevation of the contact device and Fig. 3 is a top plan thereof.

The stand 1 and the pole 2 are of ordinary construction and mounted in the usual manner upon the roof of the car. At the upper

end of the pole 2 is secured a hinge block 3 with a pin 4 on which is mounted a bracket 5 that is normally restrained by suitable means such as springs 6. These parts constitute the supporting means for my improved contact and the particular construction thereof shown in the drawing is in no way essential to the use of my device.

My contact device comprises a rectangular contact frame 7 bolted at its center to the bracket 5; and having side webs 8 rising slightly above its upper surface and retaining flanges 9 at its ends which extend upwardly and are folded over the end portions of the upper surface of the frame. In the space between the side webs 8 are disposed a plurality of parallel contact bars 10 of a thickness to extend above the webs 8 and of a length to be retained by the overhanging flanges 9, but short enough to permit of longitudinal movement. The means for effecting the longitudinal positioning of the contact bars 10 consists of set screws 11 tapped through the end flanges 9 and abutting against the ends of the bars so that in case of a groove having been cut out by the stationary conductor in the several bars 10 it is only necessary to turn back a screw 11 at one end of a bar 10 and turn up the screw 11 at the opposite end of the same bar and thereby interrupt the continuity of the groove as indicated at 12 in Fig. 3. When another groove shall have been cut in the contact bars in their new positions, the bar that was first moved or either of the others may be readjusted to interrupt the groove so as to prevent the stationary conductor from being confined to that particular part of the contact.

I do not desire to restrict myself to the particular form or arrangement of parts, since it is apparent that they may be changed and modified without departing from my invention.

What I claim as new and desire to secure by Letters Patent of the United States, is,

1. The combination with a railway contact device, of means for interrupting the continuity of grooves or ruts worn therein by the action of the stationary conductor.

2. In a railway current collector, the combination of a divided contact surface, and means for longitudinally adjusting the component parts of said surface relatively to each other.

3. In a railway current collector the combination of a frame, a plurality of parallel contact bars supported by said frame, and means for severally adjusting said bars.
- 5 4. In a current collector, the combination of a frame having overhanging end flanges, a plurality of parallel bars retained in said frame by said flanges, and adjustable screws

extending through said flanges and engaging said bars.

In witness whereof I have hereunto set my hand this fourth day of August, 1906.

ALBERT H. ARMSTRONG.
